VACUUM MOLD FOR MOLDING CONCRETE AND THE LIKE

Karl P. Billner, Philadelphia, Pa., assignor to
Vacuum Concrete Inc., a corporation of Penn-
sylvania

Application March 1, 1946, Serial No. 651,351

14 Claims. (Cl. 25—118)

1

The erection of forms for molding plastic bodies, particularly concrete, has always represented a major portion of the expense experienced with concrete structures. Ordinarily, forms are constructed, the concrete is poured, and after a substantial time, depending upon climatic conditions, the forms are torn down and for the most part, discarded.

On July 7, 1936, the present inventor received Letters Patent 2,046,867 relating to the use of subatmospheric pressures to remove the excess vehicle from newly laid concrete. As described in the patent, and contemplated herein, excess vehicle refers to that portion used to obtain sufficient plasticity for molding, but unnecessary for completion of the setting reaction. Forms of the type disclosed in the patent referred to, have been mechanically joined as disclosed in a later patent to the same inventor numbered 2,116,557, dated May 10, 1938, to define opposed form surfaces to receive the plastic mix to be molded.

It is with a view towards eliminating the necessity for any appreciable mechanical manipulation of the forms between molding operations that the present invention is proposed.

This invention is applicable for use in molding plastic bodies, including concrete, whether or not provisions are made for the removal of excess vehicle from such bodies. The use of mechanical ties is contemplated only in the event that high walls or similar constructions are being produced, and even under these circumstances, ties will be required only adjacent the top of the form elements.

Forms in accordance with the present invention for use with moldable plastic bodies are provided with means for securing them to a support, which means is responsive to subatmospheric pressure to accomplish this result. The means may comprise a sealing member for engagement with the support and connections with one or more sources of subatmospheric pressure. The sealing member may comprise a relatively flexible lip portion which will respond rapidly to the differential of atmospheric pressure externally of the securing means and reduced pressure internally thereof. The sealing means may also comprise a readily deformable sealing element of rubber or similar material to permit the forms to move to their operative positions. Suitable stops may be provided to limit the forms to such operative positions.

Where it is desired to extract or remove excess vehicle from the moldable plastic body, a perforate surface may be provided for the form ele-

ments for contact with the material being molded. Such a perforate surface or surfaces may likewise communicate with a source of subatmospheric pressure so that when the form members are in position and the body poured, excess vehicle, which may be water, will be removed through such perforate surfaces.

The supporting surface to which the forms are secured may be vertical, horizontal, or at any other desired angle, so long as the securing means defines therewith a chamber or chambers closed with respect to atmosphere so that when subatmospheric pressure is produced within such chamber or chambers, the securing action will be effected.

The present invention is applicable to the molding of walls, slabs, trusses, beams, and a large variety of other structures and structural elements as will be clear to those skilled in the art after reference to a more detailed description of the invention with reference to the accompanying drawings wherein:

Fig. 1 is a fragmentary elevation of apparatus for forming a roof truss in accordance with the present invention;

Fig. 2 is a section of the apparatus taken along line 2—2 of Fig. 1;

Fig. 3 is a sectional elevation of another form of apparatus embodying the present invention;

Fig. 4 is a sectional elevation of another modification.

With reference to Figs. 1 and 2, a suitable support 10 is provided for the forms 12, each of which is shown as having a nipple 14 for connection with a suitable source of subatmospheric pressure through hose lines 16 which communicate by means of suitable nipples 18 with a manifold 20 and pipe line 22 in which a suitable valve 24 is provided for connection and disconnection of the line with a suction pump not shown. A nipple 26 projecting from the central structure of the apparatus is connected through hose line 28 and valve 30 with the manifold 20 and the source of subatmospheric pressure. As shown in Fig. 2, a base plate 32 is received upon the support 10 upon which is superimposed a pedestal 34 of suitable material, indicated as being of concrete, containing a plurality of transverse tubular elements 36 extending therethrough and an axial tubular header 38 in communication with the nipple 26, embedded near the upper portion of the pedestal. Surmounting the pedestal there is provided a form element 40 defining the lower surface of the form proper, its upper perforate

surface being defined by, for example, one or more layers of foraminous material 42 such as screening or hardware cloth upon which is superimposed a layer of fabric 44 such as woven glass cloth. The perforate surface so formed communicates with the header 38 through a suitable number of passages 46 formed through the form element 40.

The form elements 12, shown in Fig. 2 in their extended relationship with respect to the pedestal, are provided with flexible resilient gaskets 48 of soft rubber or similar material which may be suitably fastened by means of adhesive or otherwise to the pedestal and/or form elements 12 at either side of the transverse tubular elements 36 to define vacuum chambers 50 which are maintained in communication with one another through the transverse tubular members 36.

When suction is applied to the vacuum chambers 50 through one or both nipples 14, the form elements 12 will be forced towards the pedestal by the difference between atmospheric pressure acting externally of the form elements and the subatmospheric pressure produced within the vacuum chambers. The yieldable gaskets 48 will become deformed until the inner surfaces of the form elements 12 engage the edges of the plate 32 and the form element 40, whereupon the form elements 12 will assume the positions indicated in broken lines to define a mold with the form element 40 ready for reception of the moldable plastic body. After the moldable plastic body containing excess vehicle such as a concrete mix containing excess water is introduced into the mold cavity 52 thus formed, the header 38 will be placed in communication with a source of subatmospheric pressure through the nipple 26, hose 28, valve 30, manifold 20, valve 24 and hose line 22 to extract such excess vehicle from the plastic mix through the perforate surface of the form element 40 and passages 46. After the molding operation has been completed and excess vehicle extracted from the mix, the molded body will become sufficiently self sustaining after a predetermined time to permit its removal from the form. The header 38 will be disconnected from the source of subatmospheric pressure by manipulation of the valve arrangement and subatmospheric pressure will likewise be disconnected from the vacuum chambers 50 in a similar manner. The resiliency of the gaskets 48 will bias them outwardly to the full line position shown in Fig. 2 rendering the molded body accessible for removal by suitable lifting means.

With reference to Fig. 3, the apparatus is depicted for forming beams or the like suitable for the construction of a bridge deck. The support 10 has mounted thereon a rigid form element 54 whose upper surface complements a channel. The element is provided with vertical walls 56 for cooperation with vertical form elements 58 releasably secured thereto by means of subatmospheric pressure.

The lower portions of the side forms 58 are provided with flexible resilient spaced gaskets 60 of soft rubber or like material for application to the lower vertical portion of the rigid form element 54, defining therewith and with the lower wall portion of the side form elements, vacuum chambers 62 which are placed in communication with one or more sources of subatmospheric pressure, not shown, through suitable nipples 64. Positioning plates 66 are provided at the upper and lower edges of the vertical wall portion of the rigid form to properly locate the side form ele-

ments when vacuum is applied to the chambers 62 through the nipples 64 to deform the gaskets and move the side forms towards the rigid form as the result of the differential pressure between atmosphere acting externally and the subatmospheric pressure within the chambers.

The upper portions of the side forms are provided with perforate surfaces formed of one or more layers of foraminous material 68 of screening, hardware cloth or the like surfaced with such material as woven glass fabric 70 for direct contact with the body to be molded. These perforate surfaces are placed in communication with one or more sources of subatmospheric pressure through a suitable number of nipples 72 connected with such a source of subatmospheric pressure, not shown, when it is desired to extract excess vehicle from the plastic mix. To impart the desired configuration to the molded body, the form elements may be provided with projections or indentations of the type exemplified by the projections 74 formed internally on the side forms 58.

After the material to be molded has been introduced into the cavity 76 defined by the upper surface of the rigid form element and the inner vertical surface of the side form elements, the nipples 72 may be connected with a suitable vacuum pump, not shown, and suction applied until the desired quantity of excess vehicle has been removed. Then the source of suction can be disconnected from the nipples 72 and from the nipples 64 permitting the side form elements to move horizontally from contact with the molded body to facilitate its removal.

The support 10 in Fig. 4 is depicted as receiving a pair of vertical form elements 78 provided with layers of foraminous material 80 of screen or the like over which are applied layers of woven glass or similar fabric 82 for contact with the plastic body to be molded. Communication with the perforate surface thus formed with a suitable source of subatmospheric pressure not shown is established through nipples 84 penetrating the walls 45 of the form elements. Suitably secured to the base of each of these form elements there is a flange 86 spaced from the support 10 by soft yieldable resilient gaskets 88 of rubber or similar material, the outer of which is provided with a thin lip 90 of sheet rubber or the like to facilitate rapid and positive sealing engagement with the support. Each of the vacuum chambers 92 defined by the flange 86, its spaced gaskets 88 and the surface of the support is connected with a source of subatmospheric pressure not shown through suitable nipples 84.

It will thus follow that when it is desired to position the form elements upon the support, suction will be applied to the nipples 84 whereupon atmospheric pressure will force the flanges and their gaskets downwardly upon the support securing them together, following which the plastic material will be introduced into the cavity 96 to the desired height, whereupon the nipples 84 will be placed in communication with a source of subatmospheric pressure to extract the excess vehicle from the plastic mix. As soon as the molded body becomes self sustaining the various nipples can be disconnected from the source of subatmospheric pressure and the forms readily removed to enable them to be used in connection with a new molding operation.

It will be understood that where the side forms in connection with any of the foregoing examples are particularly high, it may become

necessary to tie the upper ends together during the molding operation to prevent any tendency which they may have to separate due to the weight of the plastic material contained therebetween. The parts will be designed structurally to sustain the loads imposed upon them in a manner with which those skilled in the art will be conversant.

The foregoing illustrations and the description accompanying them represent a few of the contemplated applications of the present invention and they are not to be construed as restrictive beyond the scope of the appended claims.

Claim:

1. A form element for use with a moldable plastic body containing excess vehicle, said form element having a pervious surface for engagement with said body, related fluid actuated means for securing said element to a support, said means comprising a sealing member for engagement with said support, and connecting means for communicating said porous surface and sealing member with a source of subatmospheric pressure to position said element with respect to said support and remove excess vehicle through said surface from said body, and pressure control means for actuating said securing means exclusively of the removal of excess vehicle.

2. A form element for use with a moldable concrete body containing excess water, said form element having a pervious surface for engagement with said body, related fluid actuated means for securing said element to a support, said means comprising a sealing member for engagement with said support to form a chamber therewith, and connecting means for communicating said porous surface and sealing member with a source of subatmospheric pressure to reduce the pressure within such chamber to position said element with respect to said support and remove excess water through said surface from said body, and pressure control means for actuating said securing means exclusively of the removal of excess water.

3. A separable form for use with a concrete mix containing excess water, said form having pervious surfaces for engagement with said mix, related fluid actuated means for securing said form to a support, said means comprising a sealing member for each separable part for engagement with said support, and connecting means for communicating said surfaces and sealing members with a source of subatmospheric pressure to position said form with respect to said support and remove excess water through said surfaces from said mix, and pressure control means for actuating said securing means exclusively of the removal of excess water.

4. A form for use with a moldable plastic body which imposes a hydrostatic force thereon, related fluid actuated means for securing said form to a support, said means comprising a sealing member for engagement with said support and means for connecting said securing means with a source of subatmospheric pressure for producing a reduced pressure between said sealing member and support, said sealing member having an effective area exceeding that required by the dimensions of said form to secure proximate portions of said form to said support by subatmospheric pressure, the excess area being sufficient to secure the form against hydrostatic force imposed by said body in its plastic condition.

5. A form for use with a moldable plastic body which imposes a hydrostatic force thereon, related fluid actuated means for securing said form to a support, said means comprising a resilient sealing member for engagement with said support and means for connecting said securing means with a source of subatmospheric pressure for producing a reduced pressure between said sealing member and support, said sealing member having an effective area exceeding that required by the dimensions of said form to secure proximate portions of said form to said support by subatmospheric pressure, the excess area being sufficient to secure the form against hydrostatic force imposed by said body in its plastic condition.

6. A form for use with a moldable concrete body which imposes a hydrostatic force thereon, related fluid actuated means for securing said form to a support, said means comprising a yieldable sealing member for engagement with said support to define a chamber therewith and means for connecting said securing means with a source of subatmospheric pressure to reduce the pressure in such chamber, said sealing member having an effective area exceeding that required by the dimensions of said form to secure proximate portions of said form to said support by subatmospheric pressure, the excess area being sufficient to secure the form against hydrostatic force imposed by said body in its plastic condition.

7. A separable form for use with a moldable plastic body which imposes a hydrostatic force thereon, related fluid actuated means for securing separable parts of said form to a support, said means comprising a sealing member carried by each part for engagement with said support and means for connecting said securing means with a source of subatmospheric pressure for producing a reduced pressure between said sealing members and support, each sealing member having an effective area exceeding that required by the dimensions of said form part to secure proximate portions of said form to said support by subatmospheric pressure, the excess area being sufficient to secure the form part against hydrostatic force imposed by said body in its plastic condition.

8. A form having a perforate surface for use with a moldable plastic body containing excess vehicle, related fluid actuated means for securing said form to a support, said means comprising a sealing member for engagement with said support and means for connecting said securing means and sealing member in communication with a source of subatmospheric pressure, said sealing member having an effective area exceeding that required by the dimensions of said form to secure proximate portions of said form to said support by subatmospheric pressure, the excess area being sufficient to secure the form against hydrostatic force imposed by said body in its plastic condition.

9. A form having a perforate surface for use with a concrete mix containing excess water, related fluid actuated means for securing said form to a support, said means comprising a sealing member for engagement with said support, means for connecting said surface with a source of subatmospheric pressure to remove excess water from said body, means for connecting said securing means with a source of subatmospheric pressure for producing a reduced pressure between said sealing member and support, and pressure control means for actuating said securing

ing means exclusively of the application of pressure to said surface.

10. A form having a perforate surface portion for removing excess vehicle from a moldable plastic body which imposes a hydrostatic force thereon, a related fluid actuated sealing portion for application to a support, and means for connecting said sealing portion with a source of subatmospheric pressure for positioning said perforate surface portion with respect to said support, said sealing portion having an effective area exceeding that required by the dimensions of said form to secure proximate portions of said form to said support by subatmospheric pressure, the excess area being sufficient to secure the form against hydrostatic forces imposed by said body in its plastic condition.

11. A form having a perforate surface portion for removing excess vehicle from a moldable plastic body which imposes a hydrostatic force thereon, a related fluid actuated sealing portion adapted to define a closed chamber with respect to a support, and means for connecting said sealing portion with a source of subatmospheric pressure for positioning said perforate surface portion with respect to said support, said sealing portion having an effective area exceeding that required by the dimensions of said form to secure proximate portions of said form to said support by subatmospheric pressure, the excess area being sufficient to secure the form against hydrostatic forces imposed by said body in its plastic condition.

12. A form having a perforate surface portion for removing excess vehicle from a moldable plastic body, a related fluid actuated sealing portion adapted to define a closed chamber with respect

to a support, means for connecting said sealing portion and said perforate portion with a source of subatmospheric pressure for positioning said form in an operating position and removing excess vehicle through said surface portion from said body, and pressure control means for applying pressure to said chamber exclusively of the application of pressure to said perforate portion.

13. A form having a perforate surface portion for removing excess water from a concrete body, a fluid actuated sealing portion for application to a support adjacent said body, means for connecting said portions with subatmospheric pressure to position said form in an operating position and remove excess water through said surface portion from said body and independently operable pressure control devices for said portions.

14. A form having a perforate surface portion for removing excess vehicle from a moldable plastic body, related fluid actuated sealing means responsive to subatmospheric pressure for securing said form to a support adjacent to said body, means for connecting said surface portion with a source of subatmospheric pressure for removing excess vehicle through said surface portion from said body and independently operable pressure control means for said sealing means.
